UNITED STATES PATENT OFFICE

SYDNEY PRABERTY, OF MONTREAL, QUEBEC, CANADA

DESIGN FOR A COMBINED ADVERTISING DEVICE AND SIGNAL SUPPORT

Application filed September 12, 1929, Serial No. 32,727, and in Canada June 17, 1929. Term of patent
 $3\frac{1}{2}$ years

To all whom it may concern:

Be it known that I, SYDNEY PRABERTY, a subject of the King of Great Britain, of 909 Victoria Square, in the city of Montreal, Province of Quebec, and Dominion of Canada, have invented a new, original, and ornamental Design for a Combined Advertising Device and Signal Support, of which the following is a specification, reference being had to the accompanying drawing, forming part thereof.

Figure 1 is a side view of the combined ad-

vertising device and signal support, the signal element being shown in perspective.

Figure 2 is a front elevation of the combined advertising device and signal support.

I claim:

The ornamental design for a combined advertising device and signal support, as shown.

In witness whereof, I have hereunto set my hand.

SYDNEY PRABERTY.
